UNITED STATES PATENT OFFICE

SIDNEY VOLK, OF BENTON HARBOR, MICHIGAN

SKYLIGHT

Application filed November 17, 1926. Serial No. 148,888.

The invention relates generally to improvements in skylights of that type which is of fireproof construction and comprises a metallic frame structure made of separable members so that the skylight can be disassembled and shipped in knock-down condition.

More specifically defined, the present invention is an improvement over the skylight which is disclosed in my prior application 10 for United States Patent, Serial Number 689,277, filed Jan. 29, 1924, and an object of the present invention is the provision in a skylight of the character described having novel means for detachably securing the lower ends 15 of the inclined supporting frame members of the skylight to the base of the frame without lap joints between said inclined members and the base.

A still further object of the invention is the provision in a skylight of the character described of novel supporting frame members comprising juxtaposed light gauge metal sections secured together without the use of solder, welding, bolts, rivets or other fastening elements extrinsic to the sections themselves.

A still further object of the invention is the provision in a skylight of the character described of novel clamping devices for detachably securing superimposed members of the skylight in place on underlying supporting members.

Other objects and advantages of the invention will be apparent from the following description, considered in conjunction with the accompanying drawings, in which

Figure 1 is a plan view of a skylight embodying the present invention,

Figure 2 is a relatively enlarged fragmentary vertical section substantially on the line 2—2 of Figure 1, the top members of the inclined frame members of the skylight being omitted,

Figure 3 is a fragmentary perspective detail view of the meeting ends of adjacent side and end members of the base of the skylight frame structure,

Figure 4 is a fragmentary vertical section through a corner portion of the skylight, substantially on the line 4—4 of Figure 1,

Figure 5 is a plan sectional detail view of a corner portion of the skylight frame,

Figure 6 is a transverse vertical section through the ridge member of the skylight frame with fragmentary portions of a pair 55 of inclined supporting members of the frame shown in elevation, the top of the ridge member being omitted and the view illustrating the means for connecting the lower flanges of the ridge member with the adjacent inclined 60 supporting members.

Figure 7 is a perspective of one of the clips embodied in the invention;

Figure 8 is a perspective of one of the supporting members embodied in the invention; 65

Figure 9 is a fragmentary perspective of the ridge bar;

Figure 10 is a fragmentary perspective of the hip member;

Figure 11 is a perspective of one of the 70 clips used in conjunction with the ridge bar; and

Figure 12 is a perspective of one of the fastening elements for association with the clip disclosed in Figure 11 and the ridge bar. 75

The members of the supporting frame structure of the improved skylight are made of light gauge metal and preferably are galvanized or otherwise treated so as to be highly resistant to rust. The frame structure of the skylight comprises a base member generally indicated at 1 which may have the form of an open rectangular frame, a ridge member 2, inclined hip members 3 which connect the ends of the ridge member 2 with the adjacent corners of the base 1, a plurality of relatively long inclined supporting side members or rafters 4 which connect the opposite sides of the ridge member 2 with the side sections of the base, shorter inclined supporting 85 side members 5 which connect the adjacent hip members 3 with the side sections of the base, relatively long inclined end supporting members or rafters 6 which connect the ends of the ridge member 2 with the end sections of the base, and shorter inclined end supporting members 7 which connect the hip members 3 with the end sections of the base.

The base 1 comprises a pair of parallel side sections 1^a and a pair of parallel end sections 100

1^b. Each section of the base may be formed of a strip of light gauge metal bent longitudinally to produce the downturned vertical flange 8 and the trough-shaped body portion 9 which is substantially V-shaped in cross sectional configuration and has a downwardly and outwardly inclined flange 10 at the edge of its outer side member or portion. The flange 10 is formed with an outwardly and upwardly inclined retaining lip 11 at its edge for a purpose to be presently stated. The meeting ends of the adjacent sections of the base are cooperatively beveled. The flanges 8 of certain of the sections of the base have attaching extensions 12 as shown in dotted lines in Figure 2, each attaching extension 12 being bent flatwise against the outer base of the flange 8 of the adjacent section and secured to the latter by a suitable fastening device, 20 such as the bolt and nut indicated at 13.

The inner side members of the body portions 9 of adjacent sections of the base are formed with upturned juxtaposed flanges 14 at their meeting ends as shown in Figure 3, 25 such flanges being provided with aligned transverse openings 15. The outer side members of the portions 9 of alternate sections of the base are provided with extending attaching flaps 16 which are bent flatwise against the outer 30 side members of the portions 9 of the adjacent sections and are secured to the latter by bolts as indicated at 17 in Figure 3. The inclined supporting members 3, 4, 5, 6 and 7 are identical in construction in essential respects and each 35 comprises a main or body portion which is formed of two similar channel members arranged with their webs flatwise against each other and with the flanges of each section spaced vertically and the flanges of the two 40 sections turned oppositely as indicated at 18-18 for the sections of the hip member 3 that is partly shown in Figures 4 and 5 of the drawings. The web portion of one 45 of the pair of cooperative sections of the main or body portion of each of the aforesaid inclined supporting members may have portions thereof punched or otherwise forced laterally through an opening in the web portion of the adjacent section and clinched 50 against the latter as indicated at 19 for the fastening means of the web portions of the sections of the inclined side supporting member 4 in Figure 2, whereby the cooperative sections of the main portion of 55 each inclined supporting member will be secured flatwise to each other without the use of rivets, bolts, or solder. The upper flanges of each of the inclined supporting members 3, 4, 5, 6 and 7 are inclined downwardly toward 60 their outer edges as indicated at 20 for the upper flanges of the hip member shown in Figure 4 and the outer edge portions of such flanges are turned upwardly and outwardly as indicated at 21 in Figure 4 for a purpose 65 to be presently stated. The lower flanges of

each of the aforesaid inclined supporting members are inclined downwardly and outwardly toward their outer edges which are turned upwardly and outwardly at 23, thus producing gutters for receiving and conducting condensation to the trough-shaped portions 9 of the adjacent sections of the base.

The web portions 18 of the sections of the hip members 3 straddle the upturned flanges 14 at the meeting ends of adjacent sections of the base and are secured to the latter by bolts and nuts such as indicated at 24 which extend through aligned openings in the lapped portions of the sections 18 and the upturned flanges 14, the web portions of the sections 18 having openings aligned with the openings 15 of the flanges 14. Each of the remaining inclined supporting members is secured to the base and each of the hip members is additionally secured to the base by means of a bolt 25 having its shank partially disposed between the web portions of the sections of the supporting member and having a head comprising oppositely extending lateral branches 26 fitting in openings in the webs of the sections of the associated supporting member, the remaining portion of the shank of the bolt 25 extending through an opening in the outer side portion of the body 9 of the adjacent section of the base and being engaged by a nut 27 as shown in Figures 2 and 5. When the nut 27 has been tightened, the lower end of the associated inclined supporting member 3, 4, 5, 6, or 7, as the case may be, will be drawn tightly against the outer side portion of the body 9 of the adjacent section of the base and the lower flanges of the lower end portion of that inclined supporting member will rest on the inner side portion of the body 9 of that section of the base, all as illustrated to advantage for the inclined member 4 in Figure 2 of the drawings. It therefore will be manifest that the inclined supporting members of the frame structure of the skylight may be attached securely to the base without any necessity of providing flaps or lateral extensions at the lower ends of the inclined supporting members for connecting such inclined supporting members with the base.

The main or body portions of the inclined supporting members have their lower corner portions cut away within the trough-shaped portions of the sections of the base as indicated at 28 in Figure 2 so as to permit drainage along the portions 9 of the sections of the base and the meeting ends of portions 9 of adjacent sections of the base have openings provided at the corners of the base as indicated at 29 in Figure 5 through which moisture that has accumulated in the trough-shaped portions of the base will drain and thus will be discharged or escape outside of the base.

The body of the ridge member 2 likewise comprises a pair of similar channel members,

as at 30, having their web portions disposed flatwise against each other and secured together by punching a portion of one of such webs laterally through the other web and clinching such laterally struck portions of the first web against the second web as indicated at 31 in Figures 2 and 6. The flanges of each of the sections of the body of the ridge member are spaced vertically and are inclined 10 downwardly toward their outer edges, the lower flanges of the sections of the ridge member being indicated at 32 and being inclined upwardly and outwardly at their edges at 33. The upper flanges of the sections of the ridge member are designated at 34 and have upwardly and outwardly inclined edge portions 35.

The upper ends of the relatively long inclined supporting members 3, 4 and 6 extend 20 between the upper and lower flanges of the body of the ridge member and have attaching end flaps or extensions, as at 36 for the members 4 in Figure 2, then flatwise against the web of the body of the ridge member and secured to the latter by bolts and nuts as at 37. The sections of the body of the ridge member are additionally secured together and braced by means of clips 38 which extend 25 transversely across the lower flanges of the sections of the body of the ridge member and have side portions 39 which embrace the outer edge portions of the lower flanges 32 and extend on the upper faces of the lower flanges 32 toward the webs of the sections 30. The side portions of the clips which embrace the flanges 32 and the interposed portions of the flanges 32 may be provided with aligned openings for the reception of bolts 40. The bolts 40 serve in conjunction with nuts 31 to secure 30 the side portions of the clips 38 to the flanges 32 of the body of the ridge member and may also serve to secure attaching extensions 42 on the adjacent inclined supporting members of the frame structure of the skylight to the ridge member of the skylight frame.

The upper flanges of the inclined supporting members of the skylight frame may be covered with putty as indicated at 43 in Figure 4, flush with the edges of the upwardly and outwardly inclined outer edge portions of the flanges of said inclined supporting members. The putty of course is retained by the upwardly and outwardly inclined edge portions of the upper flanges of the inclined supporting members and serves to seal the joint between the bodies of the inclined supporting members and the adjacent edge portions of panes of glass which are supported thereon, as at 44 in Figure 4, and which rest 50 at their lower edges on the downwardly and outwardly inclined flanges of the sections of the base against the upwardly and outwardly inclined lip 11. The ridge member and each of the inclined supporting members includes 55 a cap bar designated 45 for the ridge member and 46, 47, 48, 49 and 50 for the members 3, 4, 5, 6 and 7 respectively. Each of the cap bars has downturned longitudinal edge portions as shown for the cap bar 45 in Figure 4 and each cap bar serves to cover the adjacent edges 70 of the glass panes which are partially supported by the body of the supporting members with which that cap bar is used. Each cap bar is secured in place by clamping devices each of which comprises a clip 51 having 75 its side edge portions 52 embracing the outer edge portions of the upper flanges of the body of the underlying supporting member and a bolt having a shank 53 extending upwardly through an arched middle portion 54 of the clip and having oppositely extending branches 55 at its lower end retained under the arched middle portion 54 of the clip. The shank 53 extends through an opening in the associated cap bar and is engaged by a 80 nut 56 which is tightened to secure the cap bar in place.

From the foregoing description of the various parts of the device, the operation thereof may be readily understood. The aforesaid parts of the improved skylight may be shipped in knock-down condition and the skylight assembled without the use of any unusual skill at the place where it is to be used. The base is adapted to rest on the curbing of a supporting frame structure (not shown) with the downturned flanges 8 of the sections of the base disposed within such curbing. The skylight will be fireproof and also moistureproof and any moisture which collects at the under side of the skylight and condenses will be conducted in the gutters on the lower flanges of the inclined supporting members into the trough-shaped portions of the sections of the base and then will drain 95 from the skylight outwardly of the structure on which the skylight is used. The component parts of the supporting frame structure of the skylight are well stayed to one another because of their connections with one 100 another as hereinbefore described. For example, the relatively short inclined supporting members 5 and 7 serve to brace the hip members 3 from the base and also cooperate with adjacent supporting members to support the glass panels of the skylight.

Obviously, the invention is susceptible of embodiment in forms other than that which is illustrated in the accompanying drawings and I therefore consider as my own all such 115 modifications and adaptations thereof as fairly fall within the scope of the appended claims.

I claim:

1. In a skylight, a frame structure comprising a base member having a body portion substantially V-shaped in cross sectional configuration, a plurality of inclined supporting members having their lower ends resting in 125 said body portion of the base and abutting 130

- the outer side wall of said body portion of the base, said supporting members comprising juxtaposed longitudinal sections secured together, bolts having shanks partially disposed between the sections of said inclined supporting members and extending through openings in the outer wall of the body of said base member, said bolts having lateral branches at their inner ends disposed in transverse openings in the sections of said inclined supporting members, and nuts engaged with the outer end portions of said bolts.
2. In a skylight frame structure, a substantially rectangular base comprising a pair of side sections and a pair of end sections, each of said sections being made of light gauge material and having a longitudinally extending body portion substantially V-shaped in cross sectional configuration, the meeting ends of adjacent sections being cooperatively beveled, the inner side walls of the body portions of adjacent sections having upturned juxtaposed flanges at their meeting ends, and hip members supported on the corner portions of said base member, each of said hip members comprising a pair of juxtaposed secured together sections having their lower end portions straddling the juxtaposed upturned flanges at the meeting ends of the adjacent sections of the base member and secured to said last named flanges.
3. In a skylight frame structure, a ridge member comprising a pair of juxtaposed longitudinal sections having oppositely turned flanges at their lower edges, and a clip extending transversely of said sections and having side portions embracing the outer edge portions of said flanges, bolts securing the lapped portions of the clip and said flanges together, inclined supporting members at opposite sides of said ridge member, said inclined supporting members having attaching extensions apertured for the reception of the aforesaid bolts, whereby said bolts may also serve to connect said inclined supporting members with said ridge member.
4. In a metallic building structure a substantially rectangular sectional base having inwardly directed juxtapositioned flanges at its corners, hip members extending from the corners of the base, the hip members including opposed parallel members which receive the flanges of each two adjacent base sections therebetween and removable fastenings passing through the hip members and flanges whereby to secure the base sections together and to attach the hip members to the base.
5. In a metallic building structure a substantially rectangular frame including side and end sections of substantially V-shape in cross-section, upstanding flanges on the ends of the adjacent sections, and hip members supported on the corners of the frame, each

of which includes a pair of juxtaposed longitudinal members having their lower ends disposed upon opposite sides of the flanges and secured thereto.
